UNITED STATES PATENT OFFICE

SAMUEL KAYE, OF COLUMBUS, MISSISSIPPI; B. G. HAZARD AND ROBIN WEAVER
EXECUTORS OF SAMUEL KAYE, SR., DECEASED

SIPHON CIRCULATING SYSTEM FOR AUTOMOBILES

Application filed April 15, 1927. Serial No. 184,061.

This invention relates to an improvement in siphon circulating systems for automobiles.

The object of the invention is to provide a greater circulating capacity through the radiator and the water jacket of the engine than is ordinarily obtained. This is accomplished by providing a separating chamber, a mixing tube, and a condensing chamber in the top of a radiator, an overflow pipe, and a bottom hose connection between the radiator and the engine water jacket of a capacity greater than that of all the radiator tubes combined, so as to keep a continuous circulation of water through all the radiator tubes. This causes the water to flow more freely and quickly into the engine water jacket and a continuous circulation therethrough.

The invention further provides a mixing tube to thoroughly mix the steam and water which passes from the uppermost part of the engine water jacket. The mixed water and steam forms a lighter mixture than the solid body of water in the radiator whereas the weight of the water causes this light mixture to rise above the level of the water in the radiator and flow over the top end of the mixing tube into the separating chamber, which is made a part of the radiator or else connected thereto, and through one or two passages into the condensing chamber of the radiator; where two pipes are used, one is for the passage of water and the other for the passage of steam, the steam passing through the uppermost pipe into the condensing chamber, and out through the overflow pipe, the open end of which is arranged at a point below the upper or discharge end of the mixing tube which extends into the separating chamber.

This arrangement also prevents any water from flowing back from the radiator down through the mixing tube into the top of the engine water jacket and insures of a continuous circulation through the radiator and the natural system intended for cooling the engine.

In the accompanying drawings:—

Fig. 1 is a vertical sectional view of a radi-

ator and a portion of an engine with the invention as applied thereto;

Fig. 2 is a top plan view of the same;

Fig. 3 is a detail transverse sectional view; The numeral 1 designates the engine generally, which may be of any suitable form, normally used to drive an automobile. This engine is provided with the usual form of water jacket 2 shown especially in Fig. 1.

The usual form of radiator is designated by the numeral 3 for cooling the water passing into the engine water jacket 2, and for this purpose the radiator is provided with an upper steam condensing chamber 4 and a lower radiator chamber 5, connected together by a series of small tubes 6, as shown in Figs. 1 and 2. The upper radiator chamber is provided with a plurality of horizontal tubes 7 which pass through said chamber. When the car is moving, air passes through the said horizontal tubes 7, causing the steam in chamber 4 to partly or wholly condense. The lower chamber 5 is connected to the water jacket 2 by means of an enlarged bottom hose connection 8. The capacity of the connection 8 is greater than that of the combined capacities of all of the vertical radiator tubes 6, so as to insure a more perfect circulation through the said tubes 2.

A separating chamber 9 may be formed integral with, or separate from, the upper radiator chamber 4, but is connected therewith by one or two pipes or passages 10 and 11 for water and steam respectively.

A mixing tube 12 is connected with the engine water jacket 2, and extends upwardly from the water jacket into the separating chamber 9 to a point slightly below the top of said chamber.

The lower end of the mixing tube 12 extends into the water jacket 2, and is perforated as at 13 to allow the steam to enter the mixing tube around its entire circumference and to thoroughly mix with the water which enters at the end. An overflow opening or pipe 14 extends downwardly from the upper radiator chamber 4, as shown in Fig. 1, and the upper end of this overflow pipe is arranged at a point below the top or discharge end of the mixing tube 12, in order to pre-

vent the water from ever flowing back into the water jacket through the mixing tube 12. This also insures of maintaining a space for steam in the condensing chamber 4 in the 5 top of the radiator to allow the passage of steam which separates from the water in the separating chamber to condense or pass through overflow pipe 14, thereby avoiding the creation of any steam pressure in the 10 separating chamber 9 and condensing chamber 4.

In the operation of the invention, the steam bubbles created in the engine water jacket rise to the uppermost part thereof from where 15 they pass into the mixing tube 12, where the steam and water are so thoroughly mixed as to form a lighter mixture than the solid body of water in the radiator, thereby causing this light mixture to rise above the level 20 of the water in the radiator and flow over the top end of the mixing tube into the separating chamber where the water and steam are separated by the water flowing below the top end of the mixing tube, the water 25 level being maintained at that point by the relative position of the inlet end of the overflow pipe. The most of the steam is condensed in the condensing chamber 4, and the remaining steam if any passes out through 30 the overflow pipe 14.

The increase in the size or capacity of the bottom hose connection 7 to a size greater than the combined capacities of the radiator tubes tends to cause the water to flow more 35 freely and quickly into the engine water jacket when the water in contact with the hot engine walls becomes so hot as to produce steam, thereby reducing the resistance of the water flowing out of the radiator and tending to cause the water to flow through more 40 of the radiator tubes than would be the case if the latter had a greater capacity than the bottom hose connection, which tends to increase the cooling capacity of the radiator.

45 I claim:

1. In a water circulating system, the combination with an engine water jacket, of a radiator having an upper condensing chamber therein, a separating chamber communicating with said upper condensing chamber in the upper and lower portions thereof, a tube communicating with the engine water jacket and extending into the separating chamber to a point in the upper portion thereof, and an overflow pipe extending downward from the upper condensing chamber, and having the upper end thereof at a point in said chamber below the level of the discharge end of the tube.

60 2. In a water circulating system, the combination with an engine water jacket, of a radiator having an upper condensing chamber therein, a separating chamber connected with said upper condensing chamber, and 65 communicating therewith through upper and

lower passageways, a mixing-tube connected with the engine water jacket and extending into the separating chamber to a point near the top thereof, and an overflow pipe extending downwardly from the condensing chamber and having the upper end thereof arranged at a point in said chamber beneath the level of the discharge end of the mixing-tube.

3. In a water circulating system, the combination with an engine water jacket, of a radiator having an upper condensing chamber, a separating chamber connected with said condensing chamber, a mixing-tube connected with engine water jacket and extending into the separating chamber to a point near the top thereof, and an overflow pipe in the condensing chamber and having the end thereof arranged at a point in the said chamber at a lower level than the discharge 75 end of the mixing tube.

4. In a water circulating system, the combination with an engine water jacket, of a radiator having an upper chamber, a separating chamber connected with said upper radiator chamber, a mixing-tube connected with engine water jacket, the inlet end of the said tube extending below the top surface of the water in engine water jacket, the discharge end extending into the separating chamber to a point near the top thereof, and an overflow pipe in the upper radiator chamber with the upper end at a point below the level of the discharge end of the mixing-tube.

5. In a water circulating system, the combination with an engine water jacket, of a radiator having an upper chamber, a separating chamber connected with said upper radiator chamber, a mixing tube having an end thereof extending into the engine water 90 jacket and having said end perforated, and said inlet end of the said tube extending below the top surface of the water in the engine water jacket, the discharge end extending into the separating chamber to a point near the top thereof, and an overflow pipe in the upper radiator chamber with the upper end arranged at a point below the level of the discharge end of the mixing-tube.

6. In a water circulating system, the combination of a mixing-tube with inlet end perforated and extending below the water level in an engine water jacket, and a radiator having an upper condensing chamber, having communication with the mixing tube.

7. A circulating system of the character described including a radiator having an upper cooling chamber, a separating chamber having separate connections with said cooling chamber in the upper and lower portions thereof, and an engine water-jacket having communication with the radiator and separating chamber.

8. A circulating system of the character described including a radiator having an up-

per cooling chamber, horizontally arranged condensing tubes extending across said cooling chamber above the water level therein, a separating chamber having separate connections with the cooling chamber in the upper and lower portions thereof, the upper communication being above the water level in the cooling chamber, and an engine water-jacket having communication with the radiator and separating chamber.

5 10. In a water circulating system, the combination with an engine water jacket, of a radiator having communication with the water-jacket, and a separating chamber communicating with the engine water jacket, and having a plurality of superimposed communications with the radiator.

15 20. In a water circulating system, the combination with an engine water jacket, of a radiator, a separating chamber communicating with the engine water jacket, and having separate steam and water communications with the radiator, and condensing tubes extending across the radiator above the normal water level therein.

25 In testimony whereof I affix my signature.
SAMUEL KAYE.
